UNITED STATES PATENT OFFICE.

WILLIAM N. GRISWOLD, OF NEW YORK, N. Y.

FIRE-ESCAPE.

SPECIFICATION forming part of Letters Patent No. 293,322, dated February 12, 1884.

Application filed October 29, 1883. (No model.)

To all whom it may concern:

Be it known that I, WILLIAM N. GRISWOLD, of New York city, county of New York, and State of New York, have invented certain new and useful Improvements in Fire-Escapes, of which the following is a full, clear, and exact description, reference being had to the accompanying drawings, and to the letters of reference marked thereon.

10 My invention has relation to that class of devices intended to facilitate the egress of persons from burning buildings, and now ordinarily known as "fire-escapes."

15 Among the objects of my invention are the production of a simple, cheap, durable, and thoroughly efficient fire-escape adapted to be controlled and handled by the fire-department or fire-service, applicable for use in connection with any building, and speedily made ready 20 for the purposes intended, and one which may be employed to afford egress from any window or aperture in the building without danger of accident to the escaping occupants. To accomplish all of this, the invention involves 25 certain novel and useful peculiarities of construction and arrangements or combinations of parts, all of which will be herein first fully described, and then pointed out in the claims.

In the accompanying drawings, forming part 30 of this specification, Figure 1 represents an elevation of one corner of a building to which my improved fire-escape has been applied, showing the essential parts of the apparatus in elevation. Fig. 2 is an elevation of the basket or 35 cage shown in folded position, in which position it is ready to be transported.

In both these figures like letters of reference, wherever they occur, indicate corresponding parts.

40 A represents any building in connection with which it may be desirable to use the fire-escape.

B is the main cable or wire rope of the apparatus, amply strong for the purpose, and of sufficient length to reach the tops of the highest 45 buildings. It may be one-half inch in diameter, more or less, and is made of wire because of its flexibility, strength, and capacity to withstand the effects of heat.

Affixed to the main cable B is an anchor or 50 grappling-hook, (represented at C,) the same being calculated to grapple with any object up-

on the top or other part of the building, (as with the cornice-structure,) and to serve as a point of support for the upper end of the rope. This anchor or grapple is intended to be hoisted by 55 a line or tackle connected with a shot, which is projected from a gun or mortar or other appliance applicable for the purpose of lodging it upon the roof, or otherwise hoisted. These appliances are common, and need not to be 60 herein shown.

Many forms of guns or mortars are fitted with specially-devised shells or projectiles to which a line can be attached, and any of these may be connected with the line for hoisting the anchor- 65 lines, &c., if desired.

To make doubly sure of a firm anchorage for the main cable, (a most important consideration,) the anchor C is provided with a backing-line, (of wire or other rope,) represented at D. 70 This may be projected over the building, if required, or may be made fast to any chimney or other suitable object in or on the building.

At E is a pendant of wire rope connected with the anchor or grapple, and carrying at 75 its free end a single block, F, through which block passes another wire rope or cable, G. This latter line is lighter than B, and may be about one-fourth of an inch in diameter, or more or less, as may be desired. It is intended 80 to operate as a hoisting-line.

G' is the cage, intended to be run up on the main line B, to receive the occupants of the building, or for the use of firemen for carrying up hose, fire-utensils, &c. This cage is made so 85 that its sides and ends fold together, substantially as represented in Fig. 2, being preferably constructed of wire, so that it is light and compact for transportation, and yet strong and durable enough for the uses intended. It is made 90 to move up and down upon the line B upon any suitable form of traveler, as at H, and may be provided with any form of brake, so that its descent may be under control of the occupants independently of the hoisting-line. The anchor, being located, sustains the line B and the 95 hoisting-line, and as soon as it is ascertained that the anchorage has been made secure the line G is affixed to the cage, or the traveler thereon, and the cage then hauled up. It (the 100 cage) may be brought before any window or other aperture in the building by suitably

shifting and locating the line B, using for this purpose a line, *a*, applied to a runner or bull's-eye, *b*, upon the line B. The cage, having received its load, may be lowered by the line G, 5 the line B sustaining the greatest burden. I is a cart or reel for carrying the line B, and K is a small reel for carrying the line G. These may be attached to or carried upon any hose-cart or hook-and-ladder carriage, being always 10 convenient and ready for use.

Being so constructed and arranged, the improved fire-escape is easy to handle and locate, and affords the important advantage of being applicable for use in connection with any building, however high.

Having now fully described my invention, what I claim as new, and desire to secure by Letters Patent, is—

1. In a fire-escape of the character herein set forth, the combination, with the anchor, of the main line or cable, the pendant carrying the block for the hoisting-line, and the backing-line, all connected with said anchor, and arranged to operate substantially as and for the 25 purposes set forth.

2. In a fire-escape of the character herein set forth, the combination of the anchor, the main line, backing-line, pendant having the block, the hoisting-line running through said block, and the cage arranged to travel on the main 30 line, substantially as shown and described.

3. The herein-described fire-escape, consisting of the main line, anchor, backing-line, pendant with the block, hoisting-line running through said block, folding cage arranged to 35 travel upon the main line, and reels for the lines, all combined and arranged substantially as shown and described.

4. In a fire-escape, the combination of the main line, anchor, pendant, hoisting-line, cage, 40 and the shifting-line *a*, with its runner *b*, applied upon the main line, substantially as explained.

In testimony that I claim the foregoing I have hereunto set my hand in the presence of 45 two witnesses.

WILLIAM N. GRISWOLD..
